Inventor.

Charles M. Saffrin

UNITED STATES PATENT OFFICE.

CHARLES M. LUFKIN, OF LANGDON, NEW HAMPSHIRE.

SWIVEL-PLOW.

SPECIFICATION forming part of Letters Patent No. 570,177, dated October 27, 1896.

Application filed April 30, 1891. Serial No. 391,165. (No model.)

To all whom it may concern:

Be it known that I, CHARLES M. LUFKIN, a citizen of the United States, residing at Langdon, in the county of Sullivan and State 5 of New Hampshire, have invented a new and useful Improvement in Swivel-Plows, of which the following is a specification.

My invention relates to an automatic adjusting-latch, the object of which is to facilitate reversing the plow, as shown in the accompanying drawings, in which—

Figure 1 is a side elevation. Fig. 2 is a top view. Figs. 3 and 4 are detail views.

Similar letters refer to similar parts in the several views.

The beam A, handles B B, and landside or standard C constitute the framework of the plow. The moldboard D, including point or share E, provided with wings a a, is pivoted 20 to the front end of the standard or landside C and to the rear end of the same by a V-shaped dog-brace, which is attached to the inner side of the moldboard D, on which it may be reversed from right to left, forming 25 a right-hand plow or a left-hand plow, and held firmly in position by one of the hooks b, which are screwed into the arms c c of cap F and held in position by check-nuts d d or in any convenient way. The cap F is provided 30 with a chamber which sits loosely on an upright fulcrum G, provided with a chamber e, in which is set a spiral spring f, with a bolt g, passing up through the spring f, chamber e,

and cap F, holding it firmly down on the upright G. 35

The under surface or bottom of cap F is provided with a series of inclined planes h, which correspond with a similar series i on the fulcrum G, arranged in such a manner that when the upper hook b is pushed downward the spring f is compressed. The lower hook b is raised from its catch j in the moldboard D, and the upper hook b is carried downward by means of the contraction of the spring f, operating on the inclined planes h 40 and i, into position to latch automatically into the catch j on the opposite side when the plow is reversed, and the lower hook is carried upward into position to be used as a lever for unlatching the plow when reversing. 45

I am aware that prior to my invention plows have been made with reversible moldboards and automatic latches. I therefore do not claim such a combination broadly; but 50

What I do claim as my invention, and desire to secure by Letters Patent, is— 55

In a swivel-plow, the combination of the fulcrum G, provided with inclined planes i, and chamber e, the spiral spring f, bolt g, and cap F, having inclined planes h and 60 hooks b b, all constructed and arranged to operate substantially as set forth.

CHARLES M. LUFKIN.
